UNITED STATES PATENT OFFICE.

HARRISON HURLBERT BOYCE, OF NEW YORK, N. Y., ASSIGNOR TO GILLETTE SAFETY RAZOR COMPANY, OF BOSTON, MASSACHUSETTS, A CORPORATION OF MAINE.

SAFETY-RAZOR.

1,066,703.

Specification of Letters Patent.

Patented July 8, 1913.

Application filed July 17, 1907. Serial No. 384,135.

To all whom it may concern:

Be it known that I, HARRISON H. Boyce, a citizen of the United States, residing in the city of New York, borough of Manhattan, county and State of New York, have invented certain new and useful Improvements in Safety-Razors, of which the following is a full, clear, and exact specification.

10 This invention relates to safety razors and has for an object to provide an improved and efficient adjustable guard.

My improved guard is easily and quickly adjusted in respect to the cutting edge of the blade and in its preferred form affords ample and sufficient support to the blade inwardly of its cutting edge, uniformly throughout the entire length thereof.

15 In the drawings accompanying and forming part of this specification a practicable embodiment of a form of my invention is illustrated, it of course being understood that changes of construction and details can be made within the scope of the invention 20 without departing therefrom.

Figure 1 illustrates a longitudinal section of the handle portion of the safety razor and a cross or transverse section of what might be termed the head portion. Fig. 2 25 is a plan view of the device illustrated in Fig. 1. Fig. 3 is a plan view with the blade and backing removed. Fig. 4 is a side elevation showing the parts disassembled and Fig. 5 is a side elevation showing the parts 30 assembled.

The razor is shown herein made up of a cap or backing 1 against which the razor blade is held in position by means of the guard 3. The guard is carried by a handle 4 which will be secured to it in some suitable manner as for instance by means of solder. A screw threaded stud 5 is carried by the cap or backing 1 and is engaged by a screw threaded socket in the end of a locking member rotatably mounted in the handle 4 which is made in the form of a sleeve. By this means the cap or backing and the guard may be moved one relative to the other. Positioning pins 7 are shown carried by the cap or backing and adapted to pass through suitable holes in the blade and guard for positioning and holding the blade in proper position. The outer edges of the guard are shown provided with teeth or fingers 8 which are located in position to engage the

blade inwardly of its cutting edge uniformly throughout its entire length, and in conjunction with the cap or backing to support the blade along a longitudinal zone inwardly of its cutting edge.

Upon the relative movement of the cap or backing 1 toward the guard the fingers 8 will be pressed into intimate engagement with the blade and upon the continuance or persistence of this movement the fingers will be spread outward thereby increasing the width of the guard relative to the adjacent cutting edge and in this manner limiting or restricting the amount of cut. Upon the reverse movement that of permitting the cap 70 or backing to move away from the guard the fingers will draw inward, thereby decreasing the amount of guard and increasing the working or efficient cutting edge of the blade. By this means the user of the razor 75 may regulate the cut and by reducing the amount of exposed cutting edge or efficient cutting edge reduce the closeness of the shave. If a closer shave however is desired the device will be adjusted to permit the 80 fingers to draw inward and to expose a wider efficient cutting edge.

What is claimed is:

1. In a safety razor, the combination with a handle portion, a blade retaining plate 85 member of a yielding guard member having its toothed portion arranged at an outward inclination relative to the plate, means for retaining a blade in position, and means for drawing the plate and guard toward 90 each other to vary the angle of inclination and to thereby cause the guard teeth to move outward relative to the cutting edge of the blade, substantially as described.

2. In a safety razor, the combination with a handle portion and a yielding guard member of substantially bowed formation in cross section, of a plate member extending transversely of the handle portion and having an edge adjacent to an outer portion of 100 the guard member and substantially co-extensive therewith, means for positioning and retaining a blade with its edge adjacent the guard, and means for drawing the guard and plate member toward each other to flex 105 the guard member to thereby cause the teeth to move outwardly relative to the cutting edge of the blade, substantially as described.

3. In a safety razor, the combination with 110

- 2
- a handle portion, a yielding guard member having guard teeth at its edge arranged with an outward inclination and adapted to be moved outward when pressure is applied thereto, of a plate member extending transversely of the handle portion overlying the guard member and having an edge part adjacent to the teeth of the guard member, means for retaining a blade in position with its edge adjacent the guard teeth, and means for moving the plate toward the guard member to apply outwardly moving pressure to the guard teeth, substantially as described.
- 5 10 15 20 25 30 35 40 45 50 55 60 65 70
4. In a safety razor, the combination with a handle portion, an outwardly inclined yielding guard member having a toothed edge portion bent to move outward upon pressure being applied, of a plate member extending transversely of the handle portion and overlying the guard member, means for securing the blade in position, and means for drawing the plate and guard toward each other whereby the pressure is applied to the toothed edge of the guard member for forcing the teeth outwardly relative to the edge of the blade.
5. In a safety razor, the combination with a handle portion, a yielding guard member having an edge part provided with guard teeth arranged at an outward inclination so that when pressure is applied to the said part the teeth will be moved transversely outward, of a plate extending transversely of the handle portion having its edge arranged adjacent the teeth and in length co-extensive with the guard, means for positioning the blade with its edge adjacent the guard, and means for drawing the plate toward the guard to deflect the guard teeth outward relative to the blade.
6. In a safety razor, the combination with a blade holding plate and a yielding guard having its toothed edge arranged adjacent the edge of the holding plate and inclined outwardly, of means for causing the toothed edge of the guard and the plate to approach each other, whereby the guard teeth are adjusted outwardly relative to the edge of the plate.
7. In a safety razor, the combination with a blade holding plate, of a blade held thereagainst, a guard having a yielding toothed edge portion arranged at an outward inclination to engage the blade, and means for drawing the guard onto the blade to force the guard teeth outwardly relative to the cutting edge of the blade.
8. In a safety razor, the combination with a yielding guard member bent at an outwardly extending angle having a toothed edge portion adapted to move outwardly, upon pressure being applied thereto, of a blade supporting plate member overlying the guard member, a blade supported by the plate member interposed between the same and the guard, and means for moving the blade and its supporting plate to force the guard teeth outwardly relative to the cutting edge of the blade.
- In testimony whereof, I have hereunto set my hand in the presence of two subscribing witnesses.
